Vickers-Armstrongs Limited, London, England,
a company of Great Britain

Application October 8, 1943, Serial No. 505,491
In Great Britain June 25, 1942

7 Claims. (Cl. 103—38)

1 This invention relates to hydraulic pumps of the kind which include a series of cylinders and pistons arranged radially about a common driving shaft, radial movement of the pistons within their associated cylinders resulting from rotational movement of the driving shaft and an associated eccentric in driving connection with the pistons, the degree of eccentricity of the eccentric, and effective length of stroke of the pistons being variable under the influence of the fluid pressure system. Such pumps are commonly employed on aircraft for actuating the various hydraulic services and it is necessary for such pumps to be not only compact in construction and light in weight, but also to be capable of running at high speeds and of working with extremely light anti-freezing fluids under extreme variations of temperature.

In the pump forming the subject of the present invention, variation of the eccentric is obtained by the well known ram and opposed spring method, the ram being acted upon in known manner by the pressure fluid in the pump.

According to one feature of the invention, the eccentric is slidably mounted upon the driving shaft in a direction at right angles to the shaft's axis, the shaft at the point where the eccentric is mounted thereon being of square or other suitable cross-sectional shape which will provide one or more plane surfaces over which the eccentric can slide. To facilitate sliding movement of the eccentric under the action of the control ram or springs, whilst under the influence of the piston thrust and driving torque, suitable anti-friction rollers or other bearing elements are interposed between the plane parallel faces of the shaft and the adjacent faces of the eccentric, relative movement taking place between the two parts, therefore with a minimum of friction.

According to a further feature of the invention, the fluid space above the control ram or rams contained in the driving shaft, to which space the fluid has access to exert pressure on the control ram or rams, is permanently connected with the delivery side of the pump by way of an axial boring in a floating ram mounted in an axial boring in the driving shaft. The floating ram is spherically seated into a face member driven by the shaft so proportioned to maintain a running pressure seal at the seating face of the stationary cover plate, and is sealed by the pressure fluid, a coil or other spring being associated with the floating ram for initially maintaining the contact of the face member which projects from the end of the driving shaft with a seating face formed on the adjacent surface of the cover plate or other

part of the pump casing, the boring in the floating ram being in permanent connection with a passage or passages in the cover plate leading to the delivery side of the pump, the fluid in the pump at the delivery side being therefore in permanent connection with the fluid space above the control ram or rams, the pressure exerted on the ram being thus determined by the pressure of fluid at the delivery side of the pump.

2 A further feature of the invention is the provision of a rotor attached to the driving shaft at the inlet side of the pump for the purpose of maintaining fluid circulation when the pump is maintaining pressure in the delivery pipe line without circulation of the pressure fluid, the pump being virtually in a "stalled" condition, the fluid circulated by the rotor in such a case passing via the pump casing to the fluid head tank, the fluid thence returning via the inlet pipe. This circulation ensures that the fluid in the system is kept at a uniform temperature.

The invention further resides in providing a compact construction of pump having a minimum of rotating parts, permitting extensive use of light alloys and consequently the formation of a pump which is light in weight.

In order that the said invention may be clearly understood and readily carried into effect the same will now be more fully described with reference to the accompanying drawings, wherein:

30 Figure 1 is a longitudinal vertical section of an hydraulic pump constructed in accordance with the invention.

35 Figure 2 is a transverse fragmentary section taken through the cylinder assembly and variable stroke eccentric.

Figure 3 is a sectional plan view illustrating the construction of the mechanism employed in Figures 1 and 2 for varying the effective stroke of the eccentric.

Figure 4 is a longitudinal vertical section illustrating an alternative form of hydraulic pump.

Figure 5 is a transverse fragmentary section taken through the cylinder assembly and eccentric.

Figure 6 is a sectional view of the eccentric and spring saddle incorporated in the pump illustrated by Figures 4 and 5.

Figure 7 is a longitudinal vertical section illustrating a further modified form of pump.

Figure 8 is a transverse section thereof through the cylinder assembly and its eccentric.

Figure 9 is a sectional view illustrating the construction of the operating mechanism for varying the effective stroke of the eccentric and/or pres-

sure setting incorporated in the pump illustrated by Figures 7 and 8.

Referring in the first case to Figures 1-3 of the accompanying drawings, the pump body 1 is bored radially to form a number of radially arranged cylinders in each of which cylinders is slidably mounted a piston 2, each cylinder being closed at its outer end by means of a cover plate 3, outward movement of the pistons within their associated cylinders being controlled by an eccentric 10 of variable stroke carried by a driving shaft. The driving shaft 4 is rotatably mounted within bearings 5 in a distance piece 6 which is bolted to the pump body at one end, the shaft being rotatably mounted at its opposite end within bearings 7 15 in the pump body, the shaft being extended beyond the bearings to carry a rotor 8 for the purpose of maintaining fluid circulation when the pump is maintaining pressure in the delivery pipe line without circulation of the pressure fluid, the 20 pump being virtually in a "stalled" position, i. e. idling, so as not to produce the pressure required to drive the apparatus when it is operating from the pump the fluid circulated by the rotor in such a case passing via the pump casing to the fluid head tank, the fluid thence returning via the inlet pipe. This circulation ensures that the fluid in the system is kept at a uniform temperature.

The flow of oil or other fluid to and from the 30 pistons is controlled by an eccentrically actuated valve 9, such as, for example, the self sealing type of valve forming the subject of British Patent No. 503,148.

The valve 9 operates within a recess formed in a cover plate 10 which is bolted to the pump body, the oil or other fluid entering the pump by way of the fluid admission passage 11, and leaving the pump by way of the fluid delivery passage 12. The passage of fluid to and from the cylinders under the control of the eccentrically actuated valve takes place by way of the common fluid inlet and discharge passages 13, which lead to the respective cylinders.

The said valve comprises two concentric parts 50 and 51 the outer of which, 51, is freely journaled on the inner and is driven therefrom by means of a driving pin 52 mounted in the part 50 and adapted to engage between a pair of shoulders formed on the part 51. The inner part 50 is mounted in any suitable manner on an eccentric member 53 which is associated with the shaft, and by virtue of such eccentricity the whole valve is caused on rotation of the shaft to move in an eccentric path over sealing faces 55 and 56 formed on the outer end of a cylinder block or barrel 55 and on the inner surface of the end cover 10. The inner part 50 is formed with an operative face 59 of annular form opposed to the cylinder block which is adapted to control a ring of ports such as 60 forming the outer termini of the passages 13, which are arranged in the sealing face 55 at a constant radius from the centre of the shaft while the outer part 51 is also provided with an operative face 61 adapted to slide over the inner face 56 of the end cover 11. A plurality of axially directed springs such as 62 are interposed between the two parts 50 and 51 in known manner to cause the operative faces 59 and 61 to bear against their respective sealing faces during those periods when the liquid pressure falls below a predetermined value while a suitable sealing device is also provided between the periphery of the inner part 50 and the outer part 51 in order to prevent leakage of liquid between said parts. In the embodiment illustrated the sealing device 75

comprises a ring 63 of flexible material which is of substantially U-shape in cross section and is disposed in a recess 64 formed between the parts 50 and 51. Also located on the part 50 and 5 adapted to co-operate with the ring 63 is a second ring 65 which may be formed of brass or other suitable material and provided with suitable conduits, channels or the like adapted to allow the pressure of liquid outside the valve to act on the ring 63 and cause the same to expand to effect a liquid seal between the two parts 50 and 51. The valve above described operates in such a manner that when liquid pressure is exerted from outside the valve it will act on the part 50 and force the operative face 59 of that part into contact with the sealing face 55. The pressure outside the valve also acts on the part 51 and forces the operative face 61 into contact with the sealing face 56 on the cover 11.

The pistons at their inner ends are of part spherical shape, as disclosed by the specification and drawings of co-pending patent application No. 505,490, and engage seatings in slippers 14 which in turn engage the outer surface of an annular ring 15, the latter being rotatably mounted about the eccentric, needle type bearings 16 being interposed between the eccentric and the ring 15 with the object of reducing friction between the parts to a minimum.

The eccentric 18 is slidably mounted upon the driving shaft in a direction at right angles to the shaft's axis, the shaft at the point 17 where the eccentric is mounted thereon being of square or rectangular shape, which will provide two parallel plane surfaces over which the eccentric can slide.

To enable the eccentric 18 to be moved at right angles to the axis of the shaft with a minimum of friction, rollers 20 are provided which rollers 40 are rotatably mounted upon pins 21, the rollers making contact with the plane surfaces of the shaft.

The eccentric 18 is maintained normally in its position of maximum eccentricity by a number, 45 for example four, helical springs 23 located within blind borings 24 in the shaft, the springs due to their initial compression maintaining the eccentric 18 normally in contact with the adjacent curved surface of the shaft.

50 A hollow ram 25 (see particularly Figure 1) is slidably mounted within a radial boring in the shaft, the lower end of the ram contacting the inner surface of the eccentric 18. The ram is bored axially as at 26 and is bored radially as at 55 27, the radial borings communicating with the axial boring 26, the ram being also formed with a peripheral groove 28 which communicates with the radial borings 27.

The boring 26 in the ram is connected with 60 the delivery side of the pump by way of an axial boring 29 in a floating ram 30 slidably mounted within an axial boring in the driving shaft 4. The floating ram 30 is spherically seated into a face member 31 driven by the shaft 4 and so 65 proportioned to maintain a running pressure seal at the sealing face of the stationary cover plate 10 and is sealed by the pressure exerted by the fluid on the inner end of the floating ram, a coil spring 32 being associated with the floating ram 30 for maintaining contact of the face member 31 with the sealing face on the adjacent surface of the cover plate when the fluid pressure is below that exerted by the spring. The boring in the floating ram 30 is in permanent connection with 70 75 a passage 33 in the cover plate leading to the

delivery passage 12 of the pump, the axial boring in the shaft for the reception of the floating ram and coil spring terminating in a further boring 34 leading to the blind boring containing the ram 25. In this way the fluid in the pump at the delivery side is in permanent connection with the fluid space within the ram 25, the pressure exerted on the ram being thus determined by the pressure of fluid at the delivery side of the pump. It will be appreciated that radial movement of the ram 25 in an outward direction will cause the eccentric 18 to be moved in a direction at right angles to the axis of the shaft 4 against the action of the coil springs 23 to reduce the degree of eccentricity of the eccentric, thereby decreasing the effective stroke of the pistons and reducing the output from the pump.

In this arrangement end caps 19 are arranged on opposite sides of the eccentric, the end caps being located between face plates 19a secured to the driving shaft. The end caps 19 serve to locate the component parts of the eccentric in an axial direction and also the annular ring 15 with which the slippers engage.

The distance piece 6 is provided with an additional fluid port 12a leading to the fluid head tank, so that the pump housing is always supplied with hydraulic fluid.

In the modified construction of pump illustrated by Figures 4 and 5, which is designed particularly for use on aircraft, the overall diameter of the pump being reduced to a minimum, the cylinders in this case comprise blocks 35 each of which is formed with a blind boring to form a cylinder, each cylinder containing a piston 2 slidably mounted therein, the blocks 35 being bolted to the pump body 1, jointing washers being inserted between the parts to ensure a fluid tight connection.

The arrangement of the pump is generally similar to that disclosed by Figures 1-3 and for that reason similar reference numerals are employed to indicate similar or substantially similar parts.

In this alternative construction instead of the rollers 20 engaging the plane surfaces of the driving shaft, segmental shaped blocks 19 carried by a ring 18 forming the eccentric are separated from the plane surfaces of the shaft by a series of needle type bearings 36 which are located within slots formed in a simple cage 37, the needle type bearings permitting of relative movement between the segmental shaped blocks 19 and driving shaft with a minimum of friction. The ram 25 in this case is somewhat different from that shown in the preceding construction, the ram being of the differential type and comprising two separate portions 25 and 25a, the portion 25a being of smaller diameter and projecting through a boring formed in the shaft as shown in Figure 6.

In this modified arrangement the coil springs 23 instead of being located within blind borings in the shaft are located within blind borings in members 38 carried by the shaft, the coil springs serving normally to maintain the eccentric in a position of maximum eccentricity, the members 38 serving to locate the eccentric axially.

Each piston at its inner end is bored transversely to receive a transverse pin 39 and form bifurcated parts, the pins being cut away at their ends to engage floating angle shaped retaining rings 40, the bifurcated end of each piston in known manner engaging its associated pin over a little more than half its peripheral surface to ensure that the pin and piston shall remain con-

nected together during the inward stroke of the pistons.

The pins 39 rest in arcuate shaped seatings formed in slippers 14 which in turn engage the peripheral surface of a ring 15 surrounding the eccentric and being spaced therefrom by a series of needle type rollers, the floating retaining rings serving to prevent undesired outward movement of the pistons and maintain the slippers in contact with the ring 15.

Figures 7-9 illustrate a modified pump of simple construction wherein the effective stroke of the eccentric can be adjusted, access to the adjusting mechanism being obtained by way of a sight opening 40a in the pump body, the length of travel of the ram 25 being determined by operation of the adjusting screw 41, the ram 25 being formed in two parts of different diameter and co-axially arranged, the two parts of the ram being slidably mounted within borings in the driving shaft 4, a space being left between the inner extremities of the two parts of the ram to constitute a fluid pressure space, to which space the fluid at the delivery side of the pump has access by way of an axial boring in the driving shaft and a hollow floating ram such as that illustrated in Figure 1. The arrangement is such that fluid pressure exerted on the end of the larger part of the ram will cause the eccentric to be moved laterally upon the driving shaft to decrease the degree of eccentricity of the eccentric thereby reducing the effective stroke of the pistons. Lateral movement of the eccentric is controllable by the adjusting screw 41 above referred to, the latter being in threaded engagement with a projection 42 on the eccentric. Coil springs 23 are provided located within blind borings in the driving shaft for normally maintaining the eccentric in a position in which the maximum length of stroke will be imparted to the pistons. The tension of the coil springs 23 is adjustable by adjusting screws 23a the latter being accessible through the sight opening 40a. In this case that part of the driving shaft carrying the eccentric is of square or rectangular shape, needle type bearing members being interposed between two opposite plane surfaces of the shaft and adjacent plane surfaces of the eccentric for the purpose of enabling the eccentric to be moved laterally of the shaft with a minimum of friction. In this modified form of pump the inner ends of the pistons are of part spherical form as in the case of the construction illustrated by Figures 1-3, and in this arrangement the transversely arranged pins in the pistons carry rollers at their extremities which engage slippers running on an annular ring surrounding the eccentric, the slippers each being formed with part spherical seatings to receive the part spherical inner ends of the pistons. In this arrangement each roller is formed with a retaining portion of reduced diameter which makes contact with the inner peripheral surface of an annular floating retaining ring, the retaining ring serving to restrain movement of the pistons in an outward direction.

In each construction illustrated the slidable eccentric is held at the full stroke or pumping position by the control springs, and as the fluid pressure generated rises to the predetermined maximum, the force exerted by the control ram or rams under the action of the pressure of the fluid at the delivery side of the pump overcomes the control springs and the eccentric is moved laterally of the driving shaft to a final position in which it lies approximately concentrically to the

axis of the shaft, this position corresponding to a no-delivery position, the quantity of fluid delivered by the pump being thus determined by the pressure of fluid at the delivery side.

The position of the eccentric and, therefore, the effective stroke of the pistons, is of course dependent on the fluid pressure at the delivery side.

Such a construction of pump as is hereinbefore described by virtue of its light and compact construction is particularly suitable for use on aircraft and for dealing with extremely light anti-freezing oils, and is capable of high rotational speeds.

What we claim and desire to secure by Letters Patent of the United States is:

1. In a hydraulic pump having a series of cylinders and pistons radially arranged around a common driving shaft an eccentric in operative engagement with the shaft and in driving connection with the pistons and means which is responsive to the influence of the fluid pressure in the discharge side of the pump for varying the degree of eccentricity of the eccentric and effective length of stroke of the pistons; the provision of opposed plane surfaces on the shaft and eccentric respectively, anti-friction means located between said plane surfaces, and means accommodated within the shaft for transmitting fluid pressure to said eccentric to cause same to move at right angles relative to the axis of said shaft.

2. In a hydraulic pump having a series of cylinders and pistons radially arranged around a common driving shaft an eccentric in operative engagement with the shaft and in driving connection with the pistons and means which is responsive to the influence of the fluid pressure in the discharge side of the pump for varying the degree of eccentricity of the eccentric and effective length of stroke of the pistons; the provision of opposed plane surfaces on the shaft and eccentric respectively, anti-friction means located between said plane surfaces, and a fluid actuated ram for varying the degree of eccentricity of the eccentric, said ram being located within a boring in the shaft and movable in a direction at right angles to the axis of the shaft.

3. In a hydraulic pump having a series of cylinders and pistons radially arranged around a common driving shaft an eccentric in operative engagement with the shaft and in driving connection with the pistons and means which is responsive to the influence of the fluid pressure in the discharge side of the pump for varying

the degree of eccentricity of the eccentric and effective length of stroke of the pistons; the provision of opposed plane surfaces on the shaft and eccentric respectively, anti-friction means located between said plane surfaces, and a fluid actuated ram for varying the degree of eccentricity of the eccentric, said ram being located within a boring in the shaft and movable in a direction at right angles to the axis of the shaft and means permanently connecting said ram with the delivery side of the pump.

4. In a hydraulic pump having a series of cylinders and pistons radially arranged around a common driving shaft an eccentric in operative engagement with the shaft and in driving connection with the pistons and means which is responsive to the influence of the fluid pressure in the discharge side of the pump for varying the degree of eccentricity of the eccentric and effective length of stroke of the pistons; the provision of opposed plane surfaces on the shaft and eccentric respectively, anti-friction means located between said plane surfaces, and a fluid actuated ram for varying the degree of eccentricity of the eccentric, said ram being located within a boring in the shaft and movable in a direction at right angles to the axis of the shaft a radial boring in the shaft, a hollow ram slideable in said boring with its lower end contacting the inner surface of the eccentric and means passing axially through the shaft and communicably connecting the interior of said hollow ram with the delivery side of the pump.

5. A hydraulic pump as claimed in claim 1 wherein the anti-friction means comprise rollers mounted on pins and contacting the plane surfaces of the shaft.

6. A hydraulic pump as claimed in claim 1 wherein the plane surfaces of the eccentric are formed by segmental blocks carried by the eccentric and are separated from the plane surfaces of the shaft by needle-type bearings located within slots in a cage.

7. A hydraulic pump as claimed in claim 4 wherein said hollow ram has an axially arranged blind boring and surrounding annular groove connected with said axial boring by radially arranged borings, and an axial passageway through the shaft connecting said annular groove with the delivery side of the pump.
